UNITED STATES PATENT OFFICE.

CHARLES A. CARSCADIN, OF CHICAGO, ILLINOIS, ASSIGNOR TO NATIONAL CAR EQUIPMENT COMPANY, OF CHICAGO, ILLINOIS, A CORPORATION OF ILLINOIS.

DRAW-BAR-YOKE KEY.

1,270,116.

Specification of Letters Patent. Patented June 18, 1918.

Application filed January 18, 1917. Serial No. 143,001.

To all whom it may concern:

Be it known that I, CHARLES A. CARSCADIN, a citizen of the United States, residing at Chicago, in the county of Cook and State 5 of Illinois, have invented certain new and useful Improvements in Draw-Bar-Yoke Keys, of which the following is a specification.

The drawbar and yoke of railway draft 10 rigging is generally connected by a key which is loosely mounted in suitable openings or slots therein and sometimes in the draft arms or sills. One end of the key is usually offset and a collar and cotter, or 15 similar pin, are provided to prevent dislodgment of the key which, however, is free to move in the slots. The movement of the key is sufficient to cause the collar to engage the adjacent draft arm or the side of the yoke 20 and thus shear the cotter pin. The key is then free to drift out of the slots and unexpectedly disconnect the yoke and drawbar, frequently with serious damage.

It is the primary object of my invention to 25 provide a key for connecting a drawbar and yoke constructed to insure against accidental displacement and consequent separation of the drawbar and yoke.

A further object of my invention is the 30 provision of a key for connecting a drawbar and yoke which is constrained to move with the drawbar so that its movement relatively to the yoke is limited.

Further objects and advantages of my in- 35 vention will be apparent as it is better un- derstood by reference to the following speci- fication when read in connection with the accompanying drawing, illustrating the pre- ferred embodiments thereof, in which—

40 Figure 1 is a side elevation of my invention in use;

Fig. 2 is a section on the line 2—2 of Fig. 1;

Fig. 3 is a vertical section illustrating a 45 slightly different form of key, and

Fig. 4 is a perspective view of the key illustrated in Fig. 3.

Referring to Figs. 1 and 2 of the drawing, 5 indicates a drawbar, preferably of 50 standard construction, the rearward end of which is connected to the yoke comprising arms 6 which are connected at their forward ends by webs 7. The rearward end of the drawbar 5 is provided with the usual slot

8 and the webs 7 have registering slots 9 to 55 receive the key. The drawbar 5 is hollow and is provided with interior shoulders 10 adjacent the slot 8.

My improved key comprises two sections 11 and 12, the section 11 being upset or 60 otherwise provided with a projecting portion 13 adapted to be disposed between the shoulders 10 so that this section of the key is constrained to move with the drawbar 5. The section 12 is disposed between the sec- 65 tion 11 and the rearward ends of the slots 8 and 9, it being understood that both sec- tions of the key are long enough to pass completely through the rearward end of the drawbar 5 and engage the slots 9 in the webs 70 7. The sections 11 and 12 are preferably provided with registering semi-circular de- pressions adjacent one end to receive a split pin 14 though other means for connecting the sections 11 and 12 may be employed. 75 Obviously from the construction the section 12 of the key is constrained to move with the section 11 and since the pin 14 is spaced from the adjacent web 7 a distance greater than the possible movement of the key the 80 pin can not be sheared.

Referring to Figs. 3 and 4 of the drawing the drawbar 5' is illustrated as con- 85 nected to the webs 7' of the yoke by a key comprising sections 16 and 17, the section 16 90 being upset or otherwise provided with a projecting portion 18 engaging between shoulders 19 on the interior of the drawbar 5'. The section 16 is thus constrained to move with the drawbar 5'. The sections 16 95 and 17 are preferably provided with regis- tering openings to receive a split pin 20 though other means for connecting the sec- tions 16 and 17 may be employed. Thus the section 17 is constrained to move with the 95 section 16. It will be understood that the sections 16 and 17 of the key are sufficiently long to pass entirely through the drawbar 5' and engage the slots in the webs 7' as in the preceding embodiment of my invention 100 and that the pin 20 is protected from shear- ing forces as previously described in con- nection with the pin 14 of Figs. 1 and 2.

The drawbar and yoke illustrated in the drawing are of standard construction and 105 no modifications thereof are necessary in order to employ my improved key which re- places keys now commonly in use with the

above enumerated advantages. The improved key is simple in construction, inexpensive and because it can not be displaced and lost it will result in a considerable saving in addition to overcoming the possibility of disastrous separation of cars in motion.

It will be apparent that various changes may be made in the form, construction and arrangement of the parts without departing from the spirit and scope of the invention or sacrificing any of its material advantages, the forms hereinbefore described being merely preferred embodiments thereof.

I claim:

- 15 1. In a railway draft rigging, the combination of a drawbar, a yoke, and a key connecting said drawbar and yoke, said key being freely movable with respect to said yoke and constrained to follow the lateral movements of said drawbar.
- 20 2. In a railway draft rigging, the combination of a drawbar, a yoke, and a key connecting said drawbar and yoke and having means to engage a portion of said drawbar whereby said key is constrained to follow the lateral movements of said drawbar, said

key being freely movable with respect to said yoke.

3. In a railway draft rigging, the combination of a drawbar, a yoke, and a key connecting said drawbar and yoke and comprising two sections, one of said sections being constrained to follow the lateral movements of said drawbar and the other section being constrained to move with said first-
30 mentioned section.

35 4. A drawbar yoke key comprising two sections, one of said sections having a medially disposed projecting portion, and means for connecting said sections.

40 5. A drawbar yoke key comprising two sections, one of said sections having a medially disposed projecting portion, registering depressions in adjacent portions of said sections, and a pin to engage said depressions whereby said sections are constrained to move as a unit.

CHARLES A. CARSCADIN.
